UNITED STATES PATENT OFFICE.

ALPHONSO ROCHELEAU, OF SAGINAW, MICHIGAN. ASSIGNOR OF ONE-HALF TO ASA E. WALCOTT, OF SAGINAW, MICHIGAN.

BEAN-SORTING MACHINE.

Application filed April 5, 1922. Serial No. 549,838.

To all whom it may concern:

Be it known that I, ALPHONSO ROCHELEAU, a citizen of the United States, residing at Saginaw, in the county of Saginaw and State of Michigan, have invented certain new and useful Improvements in Bean-Sorting Machines; and I do hereby declare the following to be a full, clear, and exact description of the invention, such as will enable others skilled in the art to which it appertains to make and use the same.

This invention relates to bean sorting machines and relates more particularly to improvements in bean sorters of the revolving roller type in which two rollers placed side by side and revolving in opposite directions receive the beans to be cleaned between them, the smooth and properly shaped, or good beans, traveling along the groove between the rollers, and dropping from the ends of the rollers into hoppers, while the rough or defectively shaped and split beans are seized by the rollers, passed down between them and delivered into a separate hopper.

My improvement relates more particularly to the construction and arrangement of the rollers and to the means for feeding the beans to them, whereby the objects of my invention are attained.

These objects are, first, to provide a roller construction that will enable the entire length of the roll assembly to be effectively utilized as sorting or picking surfaces, instead of having one end only of a long roller effective for that purpose, as has heretofore been common.

A further object is to provide an improved means for feeding beans to the rollers, whereby maximum production may be obtained with a minimum number of rollers.

With these and certain other objects in view which will appear later in the specification, my invention comprises the devices described and claimed and the equivalents thereof.

In the drawings, Fig. 1 is a perspective view, broken away in part, showing the bean-feeding device, the rolls, and the chutes for the separated product, the parts being shown in the drawings as separated one above the other for the sake of clearness.

Fig. 2 is a part transverse section on the line 2—2 of Fig. 3.

Fig. 3 is a central vertical section, partly broken away, of the parts shown in Fig. 2. 55

As is clearly shown in the drawings, 1, 1 indicate the usual parallel downwardly inclined roller shafts, which may be driven in any suitable manner, and 2, 2 is a plurality of pairs of short sectional rolls, the sections 60 spaced apart lengthwise the shafts 1, 1.

Each pair of short roller sections is provided with an independent feed spout, as 3, 3, these spouts being preferably rectangular holes formed in a plate or board 4 located 65 just above the top surfaces of the rolls.

A plurality of shut-off gates 5, 5 connected together by a frame 6 and each provided with a circular hole 7 is arranged to open or close feed spouts 3, 3 simultaneously. 70

8 is a movable hopper bottom formed with an elongated slot 9 adapted to register with the feed spouts 3, 3 and with the holes 7 in gates 5 when the machine is feeding. These elongated slots 9 may receive only one or two 75 beans at a time from the hopper and deliver the beans one at a time into the holes 7 of the gates 5 when the hopper bottom is vibrated by means of a suitably actuated arm 10, or its equivalent. 80

Beneath the pairs of rollers on shaft 1, 1 are boxes or chutes 11, 11, there being one box for each pair of rolls. Each box 11 opens into a trough 12 below and this trough in turn communicates with a spout 13 to 85 carry away the defective beans.

The chutes 11 do not extend under the endwise spaces between the rolls, but beans delivered from the ends of each roll section drop freely into a passageway 15, which 90 communicates with a spout 16 for the delivery of good beans.

Each pair of rolls 2, 2 is only of sufficient length to properly separate the good beans from defective beans when beans are fed to 95 the rolls through the spouts 3, 3 one at a time, although they may be fed very rapidly one after the other.

I have found in practice that it is essential to feed only one bean at a time to a rapidly revolving pair of rolls, but that the rate of feed may be so fast that the beans appear to be delivered to the rolls in almost a continuous stream. 100

As each bean drops through its feed spout 105 3, 3, it is directed forwardly, that is, toward

the high end of the bank of rolls, and it strikes exactly between the two roll surfaces, which are traveling at high speed toward each other. If the bean is smooth, 5 it lands between the rolls and on account of the slight upward direction which has been imparted to it, it hesitates for an instant between the rolls and then if rough it is pulled between the surfaces and delivered 10 into one of the chutes 11. If the surfaces of the bean is smooth and perfect it immediately travels the length of the short roll and drops off the end into the passageway 15.

By feeding to each pair of roll sections, 15 only one bean at a time and operating the rolls at high speed, I find that very short rolls, as 2, 2, may be employed because the selection takes place almost instantly, beans of rough or irregular surfaces going between 20 the rolls very rapidly and the good beans which are left are delivered into passageway 15 immediately upon the removal of the defective beans. I have found that a total length of approximately two inches is ample 25 for each roll section.

There may be as many short roll sections as desired on each shaft, but each roll section has its individual feed and its individual delivery spouts for good beans and 30 defective beans.

In the construction shown in Fig. 1, I have illustrated four such roll sections arranged on parallel shafts. It is obvious that although the beans are fed to each roll section one at a time, yet by employing, say, 35 four or more such sections preferably on one pair of shafts, the capacity of the machine is multiplied by the number of pairs of roll sections.

40 By the arrangement above described, interference or clogging caused by feeding several beans alongside of each other is avoided and the actual hourly capacity of the machine is greatly increased without increasing either its size or its cost. The accuracy of the work is greatly improved over that previously attained, as no bean, while on the live roll surface is hit by another bean and thereby improperly put through.

45 As is well known, only the slightest touch upon a bean while on the revolving surface is required to put it between the rolls and thence into the discard spout.

50 While I have shown and described the invention as applied particularly to the cleaning of beans, it is equally adapted to sorting of any other materials or particles where those particles having irregular shape and

smooth surfaces have to be separated from those having rough surfaces and irregular 60 shape.

Having thus described my invention, what I claim and desire to secure by Letters Patent is:

1. In a machine of the class described, a 65 pair of parallel inclined shafts, a plurality of short roll sections on each shaft, the ends of successive sections spaced apart lengthwise to form passageways for escape of material between said ends, means for feeding beans one at a time between the ends of each pair of short roll sections, a collecting spout beneath each pair of roll sections adapted to receive material passed between the peripheries of the rolls, and a spout beneath the spaced ends of each pair of roll sections to receive material passed lengthwise said sections. 70

2. In a machine of the class described, a 75 pair of parallel shafts, a plurality of rapidly revolvable short roll sections on each shaft, the ends of successive sections spaced apart lengthwise to form passageways for escape of material between said ends, and means 80 adapted to feed beans substantially one at a time to each pair of short roll sections. 85

3. In a machine of the class described, a 90 pair of parallel shafts, a plurality of revolvable short roll sections on each shaft, the ends of successive sections spaced apart lengthwise to form passageways for escape of material between said ends, means adapted 95 to feed beans one at a time to each pair of short roll sections and a plurality of spouts, one located beneath the end of each pair of roll sections, to receive material delivered between the spaced ends of said sections, for the purposes set forth. 100

4. In a machine of the class described, a 105 pair of parallel inclined shafts, a plurality of short yielding-surfaced roll sections on each shaft, the ends of successive sections on each shaft spaced apart, a collecting spout beneath each pair of roll sections, a spout beneath the spaced ends of each pair of roll sections, and means adapted to feed beans rapidly one at a time to one end of each of said pairs of short roll sections. 110

5. A bean sorting machine characterized 115 by pairs of sorting rolls each comprising a plurality of short roll sections spaced apart lengthwise, and means for feeding material onto an end of each of said pairs of roll sections, for the purposes set forth.

In testimony whereof I affix my signature.

ALPHONSO ROCHELEAU.
